MACHINE FOR ASSEMBLING WIRE BAILS ON BROOM CAP HANDLES

Spencer C. Tuttle, Waterbury, and Clyde W. Garthwait, Jr., Cheshire, Conn., assignors to Cly-Del Mfg. Co., Waterbury, Conn., a corporation of Connecticut

Application September 13, 1951, Serial No. 246,497

8 Claims. (Cl. 1—187)

This invention relates to broom handle caps and more particularly to a machine for automatically assembling wire bails on caps of the type commonly used on the ends of the handles of brooms, whisk brooms, mops, etc.

One object of the invention is to provide a dependable machine for automatically securing the ends of a pre-formed looped wire bail in the opposite sides of a pierced broom handle cap.

Another object is to provide a machine of the above nature including mechanism for accurately prepositioning the caps prior to the closure of the wire bails therein.

A further object is to provide a machine of the above nature capable of being easily adjusted for use in assembling various sizes of caps and bails.

A further object is to provide a machine of the above nature including means to prevent damage to the machinery in case of accidental jamming of the caps therein.

A further object is to provide a device of the above nature which will be relatively simple in construction, easy to install and manipulate, compact, and very efficient and durable in use.

With these and other objects in view, there has been illustrated on the accompanying drawings one form in which the invention may conveniently be embodied in practice.

In the drawings:

Fig. 1 illustrates a side elevational view of the improved broom cap assembling machine.

Fig. 2 is a front end view of the same.

Fig. 3 is a plan view of the same.

Fig. 4 is a sectional view taken along the line 4—4 of Fig. 3, illustrating on an enlarged scale, with portions broken away, the cap guide and alignment mechanism.

Fig. 5 is a horizontal enlarged cross-sectional view, taken along the line 5—5 of Fig. 4.

Fig. 6 is a horizontal enlarged cross-sectional view, taken along the line 6—6 of Fig. 4.

Fig. 7 is a horizontal enlarged cross-sectional view, taken along the line 7—7 of Fig. 4.

Fig. 8 is an enlarged perspective view illustrating details of the bail pickup and slide mechanism.

Fig. 9 is an enlarged perspective view illustrating how a bail is carried forwardly prior to its being bent into locking engagement with its cap.

Fig. 10 is a view, similar to Fig. 9, but showing the bail after it has been secured within its cap.

Fig. 11 is an enlarged vertical cross-sectional view illustrating how an assembled bail and cap unit is upset and dropped into the chute upon withdrawal of the bail pickup slide mechanism at the conclusion of its operating cycle.

Attention is called to our copending divisional application Serial Number 306,838, filed August 28, 1952, claiming the mechanism for feeding the bails to the broom cap assembling apparatus.

Referring now to the drawings, in which like reference numerals denote corresponding parts throughout the several views, the numeral 10 indicates generally the im-

2

proved cap-assembling machine, the same comprising a supporting frame 11 having integrally formed therewith a pair of front legs 12, 13 and a pair of rear legs 14, 15.

The frame 11 has fixed at the top thereof a horizontal top plate 16.

An electric motor 17 is provided for operating the machine, the same being mounted on a support shelf 18 fixed between a pair of angle iron brackets 19, 20, mounted respectively between the pairs of legs 12, 14 and 13, 15.

A pair of drive shaft bearings 21, 22 are mounted against the frame legs 12, 13, respectively, for rotatably supporting a relatively heavy drive shaft 23. A driven pulley 24 is fixed on the drive shaft 23, the same being positioned in horizontal alignment with a small drive pulley 25 mounted upon the output shaft of the motor 17. A belt 26 interconnects the driven pulley 24 with the drive pulley 25 to rotate the drive shaft 23.

Referring to Fig. 2, it will be seen that the drive shaft 23 extends through the bearing 21 and the frame leg 12, and at its outwardly-extending end is furnished with a heavy fly wheel drive pulley 27 which is in alignment with a larger driven pulley 29 fixed on a shaft 30 journaled in a bearing 31 secured to the inside of the frame leg 14, and also journaled in a bearing 32 bracketed on a horizontally-extending support member 33 secured to the inner sides of the end legs 14, 15.

The heavy drive shaft 23 has fixed thereon a drive pulley 34, positioned between the bearing 21 and the driven pulley 24 which is operatively interconnected by means of a round belt 35 with a larger pulley 36 fixed on a shaft 37 at right angles to the shaft 23 and journaled in a bearing bracket 38 secured to the top plate 16 at the front edge thereof. A drive pulley 39, smaller in diameter than the pulley 36, is also secured on the shaft 37 and serves to drive the cap guide into the alignment mechanism to be described later.

The pulleys 34, 36 are relatively offset, and a belt guide pulley assembly 40 is employed to properly direct the path of the belt 35 interconnecting said pulleys. The belt guide pulley assembly 40 comprises a substantially rectangular vertical support plate 41 mounted against the front end of the frame 11, as by bolts.

Journalized between the sides of a rectangular cut-out, in the lower portion of the support plate 41, is a short shaft 44 on which is mounted a pair of spaced-apart guide rollers 42, 43, the shaft 44 being parallel to the shaft 23. A second pair of guide rollers 45, 46 are rotatably mounted on stub shafts extending at right angles from the upper portion of the support plate 41, the axes of rotation of said rollers 45, 46 being parallel with the axis of rotation of the pulley 36.

Referring to Figs. 1 and 2, it will be seen that the belt 35 passes over the guide roller 43, upwardly over the guide roller 46, thence around the pulley 36, over the guide rollers 45 and 42 thence around the lower end of the pulley 34 to complete the drive connection between the pulleys 34 and 36.

The shaft 30, extending through the bearings 31, 32, has fixed on the inner end thereof a disk wheel 47 provided with an outwardly-extending stud pin 48 fixed within the outer face thereof.

Cooperative with the stud pin 48 is a box cam mechanism 49 fixed against the side of an upstanding rocker arm 50, swingably mounted at its lower end on a pivot pin 51 fixed between a pair of vertical brackets 52, 53 and secured against a vertical mounting plate 54 fixed between the rear legs 14, 15 at the lower ends thereof.

The box cam mechanism 49 comprises a U-shaped member 55 (Fig. 3) surrounding the outer edge of the rocker arm 50 to provide an inner bearing surface for the stud pin 48—said U-shaped member 55 being held in

place by a pair of upper and lower bolts 56, 57 respectively. The bolts 56, 57 are embraced by spacers 58, 59 holding an outer bearing plate 60 in parallel spaced alignment with the bearing surface of the U-shaped member 55. It will be understood that as the wheel 47 rotates, the stud pin 48 will move up and down between the bearing surfaces of the box cam mechanism 49, causing the upper end of the swinging rocker arm 50 to reciprocate within a longitudinal slot 61 in the top plate 16 through which it extends.

The upper end of the rocker arm 50 is operatively connected to the bail pickup slide mechanism indicated generally by the numeral 62 (Figs. 9 and 10), which comprises a longitudinally-grooved, elongated slide base 63 fixed against the top plate 16 forwardly of and in alignment with the slot 61 of said plate. Within a grooved base 63 is slidably disposed a rabbeted slide member 64 having a pair of opposed stepped portions 65, 66 of reduced thickness and with the upper surfaces thereof flush with the upper edge surfaces of the slide base 63.

In order to guide the slide member 64 within the base 63, a pair of longitudinal upper clamp strips 67, 68 are provided, such strips being fixed in position as by machine screws 69 against the upper side edges of the base 63 and overlying the stepped portions 65, 66 of said rabbeted slide member 64.

Resiliently connected to the front end of the slide member 64 and slidably therewith in the slide base 63 is a bail carrying slide block 70 (Figs. 8, 9, 10), which is provided with a pair of rearwardly-extending parallel connector rods 71, 72 having outturned ends disposed in L-shaped grooves 73, 74 at the forward end of the slide member 64. Coil springs 75, 76 embrace the connector rods 71, 72, respectively. The grooves 73, 74 are of such size as to allow considerable longitudinal movement of the bail-carrying slide member 70 with respect to the slide block 64 against the resiliency of the springs 75, 76.

A pair of longitudinal bail-closer blades 77, 78 are fixed in a pair of recesses 79, 80 located in said slide member 64—said blades being held securely in place there-in by one or more transverse clamps 81 (Figs. 3, 9), fixed to said slide member, as by machine screws 82. The forward inner edges of the blades 77, 78 are inclined outwardly as indicated by the numerals 83, 84, and lie within grooves formed by recesses in the bail-carrying slide block 70 similar to those of the slide member 64. It will be noted that the blades 77, 78 are loosely attached to the bail-carrying slide block 70, whereby a relative longitudinal movement of the slide block 70 with respect to said blades is permitted.

Referring to Figs. 1, 3, 8, and 11, the numeral 85 indicates generally a feeding rack for the preformed V-shaped looped wire bails B. The rack 85 includes a vertical bar 86, substantially triangular in cross-section, fixed to the top plate 16 in any convenient manner, as by the inclined brackets 87 (Figs. 1 and 3). The lower end of the bail bar 86 extends to a position just above the top surfaces of the blades 77, 78 and the bail-carrying slide block 70, the latter being reduced in thickness at its sides and forward end, as indicated by the numeral 88 (Figs. 9, 10, and 11), by an amount equal to the thickness of the wire of the preformed bails B.

Thus, referring to Fig. 8, it will be evident that when the bail-carrying slide block 70 is withdrawn to a position where the blades 77, 78 and the upper surface of said bail-carrying slide member are clear of the lowermost bail B, the latter will drop onto the forward end of said block 70. Subsequently, when the bail-carrying slide block 70 is moved forwardly, it will carry with it the lowermost bail B.

The forward end of the block 70 is provided with a cut-out curved recess 89 for clearance about a cap during the assembly thereon, and is provided with an upstanding withdrawal pin 90 centrally located just forward of the position of the inner rear end of a bail B.

The upper end of the bail rack bar 86 is preferably provided with an upwardly-extending pair of locating pins 91 (Figs. 1 and 3), whereby other similar rack bars loaded with wire bails may be aligned and connected therewith when loading the machine with bails.

Adjustable means is provided for operatively interconnecting the rocker arm 50 with the slide member 64 of the bail pickup and slide mechanism 62. To this end, there is secured to the rear end of the slide member 64, 10 as by the bolts 92 (Fig. 1), a rearwardly-extending bracket 93, carrying a hardened roller 94 in the outermost end thereof, said roller being in horizontal alignment with the rocker arm 50.

The rocker arm 50 is provided near its upper end with 15 a U-shaped shoe member 95 (Figs. 1 and 2), embracing the inner edge of said rocker arm 50 and pivoted thereto as by the pivot pin 96. The shoe member 95 is disposed between the rocker arm 50 and the cylindrical face of the roller 94, and the distance between the upper end of 20 said shoe member and the rocker arm may be adjusted by means of a headed screw 97 passing edgewise into said rocker arm and abutting the inside of the shoe member 95.

The upper end of the rocker arm 50 is apertured at 25 97a to retain one end of each of a pair of connector tension springs 98, 99 (Figs. 1 and 3), the forward ends of said springs being connected to a bracket 100 fixed to the top surface of the slide member 64 as by machine screws 101. The springs 98, 99 serve to maintain the 30 roller 94 in contact with the rocker arm shoe member 95, and said shoe member 95 is maintained in contact with the inner end of its adjustment screw 97, whereby the swinging motion of the rocker arm 50 will cause the slide member 64 to be reciprocated longitudinally in the 35 slide base 63.

Referring now to Figs. 1, 2, and 3, the numeral 102 indicates generally the cap guide and alignment mechanism for prepositioning the preformed caps C prior to the automatic attachment of the preformed bails B 40 thereon.

The cap guide and alignment mechanism 102 comprises an upright, elongated, rectangular back plate 103, fixed as by an angle bracket 104 (see Fig. 11), and machine screws 105, 106 to the top of a cap seat block 107, which, in turn, is secured to the horizontal top plate 16. The back plate 103 forms the rear surface of a vertical raceway, indicated by the numeral 108 (see Fig. 4), within which the caps C move downwardly by gravity, one by one, into position for the assembly of the bails B 50 thereon.

The upper portion of the raceway 108 comprises a pair of side rails 109, 110 and a central offset front rail 111, said side rails being held in spaced relation with respect to the back plate 103 by bolts 112 and spacers 113 (see Fig. 5). The front rail 111 is centrally fixed to a plurality of cross-brackets 114 (only one being shown), secured on the bolts 112 and spaced forwardly of the side rails 109, 110 by spacers 115.

It will be understood that the caps C will be fed into the raceway 108 automatically from any standard type of rotating hopper (not shown) commonly employed in the art.

The preformed caps C are provided with opposed side apertures 116 (see Figs. 4 and 6), into which the ends of the bails B are to be forced. For this purpose in 65 order that a bail, horizontally disposed on the bail carrying slide block 70, may be assembled to a cap C, it is necessary that said cap must be positioned so that its apertures are horizontally aligned. To this end provision is made of a pair of aligning wheels 117, 118 disposed below the ends of the side rails 109, 110 for rotation in a common vertical plane. The edges of the wheels 117, 118 are beveled and so spaced to allow a cap C to drop through to the lower portion of the raceway 108, 70 only when the apertures 116 are in horizontal alignment.

i.e., when the smaller diameter of the cap coincident with the common axis of the apertures 116 is in horizontal position.

Referring now to Fig. 6 it will be seen that the wheels 117, 118 are fixed to shafts 119, 120, journaled in a pair of fixed bearing members 121, 122 secured against the rear surface of the back plate 103, as by machine screws 123. The outer ends of the shafts 119, 120 are provided with grooved pulleys 124, 125 respectively, which are interconnected by a belt 126 with the drive pulley 39, previously described (Figs. 1 and 2). It will be seen that the pulleys 124, 125 will both be rotated in a clockwise direction, as viewed in Fig. 4, causing the wheels 117, 118 to turn the cap C resting against said wheels until the apertures 116 are in horizontal alignment, whereupon said cap C will drop down by gravity into the lower portion of the raceway 108.

The lower portion of the raceway 108 is similar to the upper portion except that it comprises side rails 127, 128 which are closer together and spaced apart by a distance equal to the smaller diameter of the caps C, whereby said caps will be kept in proper alignment for receiving the bails B when they reach the bottom of said raceway 108.

The end of the front rail 111 terminates at a sufficient distance above the top surface of the bail-carrying slide member 70 to allow clearance for outward withdrawal of the lowermost cap C upon operation of the machine, hereinbelow detailed.

The vertical side rails 127, 128 are provided with a pair of horizontal slots 129, 130, whereby they may be adjusted laterally with respect to their securing bolts 131, 132, whenever desired to accommodate caps of different sizes.

The cap seat block 107 is semi-cylindrically recessed, as indicated by the numeral 133 (Figs. 4 and 9), to provide a seat within which the lowermost cap C will rest while the bail B is being attached thereto.

Provision is also made of adjustable means comprising a pair of horizontal slide plates 134, 135 slidable within transverse aligned slots 136, 137 (Figs. 4, 7, 9, and 10), within the cap seat block 107, to more accurately hold the lowermost cap C on its seat 133. The slide plates 134, 135 are urged inwardly by a pair of tension springs 138, 139, connected to said slides and to a pair of outwardly extending pins 140, 141 (Fig. 4), located at the outer ends of said slide plates 134, 135, respectively.

A pair of adjustment screws 143, 144 (Fig. 4) having cylindrical knurled heads projecting into notches 145, 146 of the slide plates 134, 135 are threaded into the ends of the cap seat block 107, said screws permitting manual adjustment of the space between the inner ends of said slide plates for snugly admitting and holding the lowermost cap C.

Referring to Figs. 9 and 10, it will be seen that the lowermost ends of the vertical side rails 127, 128 are slidably fitted into slots in the upper portion of the cap seat block 107, and that said rails are in vertical alignment with the slide plates 134, 135.

The inner ends of the slide plates 134, 135 and the cap seat block 107 are provided with aligned opposed horizontal slots 147, 148 (Fig. 9), for admission of the inturned ends of the preformed wire bails B, as will be understood from the following description of the operation of the machine.

In order to upset and eject the assembled caps C and bail B, provision is made of means comprising a transverse rod 149 (Figs. 10 and 11), held in the path of the rearward motion of said assembled cap and bail, as by the angle bracket 150.

Referring to Fig. 11, it will be seen that the assembled cap will be automatically struck and upset by the rod 149 so that it will drop through an opening 151 in the slide base 63 and an opening 152 in the top plate 16 into a guide chute 153 fixed against the underside of the

slide base 63 and the cap seat block 107 as by machine screws 154.

Operation

- 5 As hereinabove explained, the slide member 64 will be continuously reciprocated in accordance with the rocking motion of the rocker arm 50. In the rearmost position of the slide member 64, a preformed V-shaped looped wire bail B will drop from the triangular bar 85 and seat itself upon the bail-carrying slide member 70, as illustrated in Fig. 8. The slide member 64, together with its resiliently connected bail-carrying slide block 70, will slide forwardly until the forward end of said bail-carrying slide member 70 abuts the inner end of the cap seat block 107. 10 Continued forward sliding motion of the slide member 64 against the tension of the coil springs 75, 76 will cause the bail-closing blades 77, 78 to slide inwardly over the bail-carrying slide block 70 and engage the outer opposed sides of the bail. This will force the bail forwardly so that 15 its apex will engage the withdrawal pin 90 (Figs. 9 and 10). At this point in the operation of the machine, the ends of the bail B being operated upon will be disposed in the pair of slots 147, 148, in alignment with the apertures 116 of a cap C prepositioned in the recess 133 (Figs. 9 and 10). 20 As the bail closer blades 77, 78 continue to move forwardly, the opposite sides of the bail will be moved inwardly to force the ends thereof into the cap apertures 116, thereby completing the assembly operation. Having now completed its forward stroke, the bail-pickup slide mechanism 62 will commence its backward stroke. The rearward motion of the bail-carrying slide block 70 will, by means of its withdrawal pin 90, pull out the assembled cap C from the cap seat block 107 and permit it to be ejected by the horizontal rod 149 and to allow the next 25 cap to fall into place for assembly of the bail B thereto. Having completed an assembly operation, the bail pickup slide mechanism 62 will continue to travel rearwardly to withdraw another bail B, whereupon the above-described cycle will be repeated indefinitely. 30 It is to be understood that while the machine is in operation the aligning wheels 117, 118 will rotate continuously and will furnish a supply of horizontally aligned caps C as rapidly as needed. 35 One advantage of the improved cap-bail assembly machine herein disclosed, is that if the bail pickup slide mechanism should accidentally jam, the resiliency of the roller-rocker connector springs 98, 99 will prevent the possibility of damage to the machine. 40 Another advantage of the improved cap assembly machine herein disclosed is that it may readily be adjusted for the assembly of caps and bails of different sizes. 45 While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the 50 following claims. 55 Having thus fully described the invention, what is claimed as new, and for which it is desired to secure Letters Patent, is:
1. In a machine for assembling pre-formed looped wire bails having inturned ends to hollow broom handle caps having apertures on opposite sides thereof, a block having a concave seat to hold said caps with their apertures in horizontal alignment, a bail pick-up slide having a top recess for holding a single bail and moving it so that 60 the ends of said bail will be in alignment with the apertures in said cap, said slide carrying an upstanding pin for successively withdrawing bails from a vertical stack located above said slide, said slide having a pair of bail-closing blades with inclined diverging ends, means to 65 advance said slide to cause said diverging ends to force the

inturned ends of said bail to move into said cap apertures, and means to cause said withdrawal pin to extract said assembled cap and bail from its seat in said block on the reverse movement on said slide.

2. The invention as defined in claim 1, in which provision is made on the base of said machine of a horizontal rod in the path of the assembled cap and bail to eject it downwardly into a receptacle located therebelow.

3. The invention as defined in claim 1, in which a motor-operated rocker arm is provided for continuously reciprocating said slide, and adjustable spring means are provided for connecting the end of said rocker arm to said slide.

4. The invention as defined in claim 3, in which said rocker arm is continuously vibrated by means of a motor operated rotating disc having a stud for engaging said rocker arm.

5. The invention as defined in claim 4, in which said stud is embraced by a box cam secured to an intermediate portion of said rocker arm.

6. The invention as defined in claim 1, in which said

bails are mounted in a bail block resiliently and yieldably connected to the forward portion of said slide by means of springs.

7. The invention as defined in claim 1, in which a pair of spring pressed aligned cross slide plates are mounted in said block with their inner ends adjustably engaging the caps to hold them within said blocks.

8. The invention as defined in claim 7, in which the inner ends of said cross slide plates have aligned slots shaped to freely embrace the inturned ends of the pre-formed wire bails.
